HINGE

George H. Johnson, Rockford, Ill., assignor to
The Atwood Vacuum Machine Company, Rock-
ford, Ill., a copartnership composed of James T.
Atwood and Seth B. Atwood

Application July 3, 1933, Serial No. 678,789.

1 Claim. (Cl. 16—179)

This invention relates to hinges for the doors of motor vehicles and is particularly concerned with a novel type of hinge and mounting therefor with a view to avoiding any projection of the hinge from the body and keeping the hinge completely concealed.

The principal object of my invention is to provide a hinge which in its preferred form has the member on the body slidably inwardly and outwardly in a guide and has the other member on the door connected with mechanism for imparting sliding movement to the body member in the swinging of the door in opening and closing, whereby to move the hinge axis of the door outwardly from a point behind the plane of the outside of the body in the opening of the door for the required clearance between the door and body, and to return the hinge axis in the closing of the door. It is realized that any suitable means may be provided for support of the body member to allow for movement thereof in and out, and the invention in its broader aspect is, therefore, more concerned with the provision of means operable by the door member in its swinging movement relative to the body member to cause the latter to move a predetermined distance in the opening of the door, according to the extent of bulge of the body which the door has to clear in opening.

Other objects of the invention will be made to appear in the course of the following detailed description in which reference is made to the accompanying drawings, wherein—

Figure 1 is a side view of a portion of an automobile body showing the flush exterior secured at the joint line of the door when hinges made in accordance with my invention are used;

Fig. 2 is a view looking in the direction indicated by the line 2—2 of Figure 1, showing the door opened;

Fig. 3 is a section on the line 3—3 of Figure 1, on a larger scale, showing the concealed hinge in plan view;

Fig. 4 is a view on the line 4—4 of Fig. 3 looking at the end of the hinge;

Fig. 5 is a fragmentary elevational detail of a hinge along the lines of Fig. 3, showing a modified or alternative construction;

Fig. 6 is a section on the line 6—6 of Fig. 2, showing the hinge parts in the positions assumed when the door is opened;

Fig. 7 is a face view of the parts appearing in Fig. 6;

Fig. 8 is a fragmentary detail of a hinge along

the lines of Fig. 7, showing a modified or alternative construction;

Figs. 9 and 10 are views similar to Figs. 3 and 4, showing a hinge of a different construction but operating on the same principle;

Fig. 11 is a section on the line 11—11 of Fig. 9;

Fig. 12 is a section like Fig. 6, but showing the hinge of Figs. 9 to 11;

Fig. 13 is a view similar to Fig. 2, showing still another hinge operating on the same principle as the others but having the body member suspended on an oscillating link instead of slidably in a guide;

Figs. 14 and 15 are horizontal sections of this hinge showing the door in closed and open positions, respectively, and

Fig. 16 is a vertical section on the broken line 16—16 of Fig. 14.

Similar reference numerals are applied to corresponding parts throughout the views.

Referring first to Figs. 1 to 4, 6 and 7, 10 indicates a portion of an automobile body on which a door 11 is hinged. The hinges, in accordance with this invention, are completely concealed and are, therefore, indicated in dotted lines at 12 and 13 in Figure 1 in proper relation to the joint line 14 of the door 11. Since the hinges do not project, the exterior of the body is substantially flush at the joint line 14, which is something particularly desirable in stream-line designs.

Each hinge proper is similar to an ordinary butt type hinge and comprises members 15 and 16 pivotally connected by a pintle 17. The member 15, because of its mounting on the body 10, will for convenience be referred to as the body member, and the member 16 will be referred to as the door member, since it is fastened by screws 18 to the door 11. Of course, any suitable fastening might be provided for the door member 16. A plate 19, suitably secured to the door pillar 20 of the body 10, as by screws 21, has guideways 22 along the top and bottom edges slidably receiving the body member 15 of the hinge for movement from the retracted position shown in Fig. 3, to the extended position shown in Figs. 6 and 7. It is necessary to have the body member 15 move out in the opening of the door in order to bring the hinge axis 17 from a point behind the plane of the outside of the body to a point far enough outside the body so that the door has the required clearance with reference to the body in its swinging movement with respect thereto. The need for this comes not only from the fact that the hinge axis 17 is behind the plane of the outside of the body when the door is closed (see Fig. 3), but also

because of the fact that the door and body are outwardly bulged and the body would interfere with the movement of the door if the hinge axis were not moved out to the proper distance (see Fig. 6). Movement may be communicated to the body member 15 in several different ways, as we shall see presently, but the mechanism for accomplishing this in the hinge now under consideration comprises an actuating lever 23 pivoted intermediate its ends, as at 24, on the body member 15, and connected at its opposite ends to the door member 16 and guide 19. The connection between the door member 16 and lever 23 is provided by a link 25 pivoted at one end to the door member 16, as at 26, and at the other end to the lever 23, as at 27. The operating connection between the lever 23 and guide 19 is provided by another link 28 pivotally connected at one end to the guide 19, as at 29, and at the other end to the lever 23, as at 30. The body member 15 is slotted, as at 31, to allow the lever 23 to project therethrough, and another slot 32 is provided in the guide 19 through which the lever 23 projects for its link connection with the bracket 33 on the back of the guide 19. There are really two links in a couple both at 25 and 28, but of course, these details may be simplified by the use in each of these two instances of a single link having a forked end, such as that shown at 25' in Fig. 8. It is also apparent that instead of having the link connection 28, the lever 23 could be extended slightly, as shown at 23' in Fig. 5, and carry a cross-pin 34 in the end thereof for sliding engagement in an elongated slot 35 provided in a bracket 33' on the back of the guide 19 to provide a seat for the door member 16 of the hinge, and another recess 37 is provided in the door pillar 20 to provide a seat for the guide 19. It is also necessary to provide a small recess 38 in the pillar for the projecting end of the lever 23 and its link connection 28 with the guide 19. Inasmuch as the hinge will be furnished completely assembled to the car manufacturer, it is necessary to provide holes 39 in the body member 15 of the hinge in register with two of the holes 40 in the guide 19 for the screws 21 which fasten the guide to the pillar. The holes 39 come in register with the holes 40 in the open position of the door, as clearly shown in Fig. 7.

In operation, assuming the door 11 is closed as illustrated in Fig. 3, it should be clear from the foregoing description that as the door starts to open, the link 25 exerts a pull upon the outer end of the actuating lever 23 tending to move the same in a clockwise direction, as the parts are viewed in Fig. 3. As a result, the fulcrum 24 of the lever 23 is caused to move outwardly relative to the body 10, that is, to the left as the parts are viewed in Fig. 6, owing to the fact that the inner end of the lever 23 is tied to the guide 19 by the link connection 28, or pin and slot connection shown in Fig. 5, as the case may be. The movement of the door in opening is limited by the engagement of the lever 23 with the end of the slot 32 in the guide, as clearly appears in Fig. 6. On the other hand, in the closing of the door, the link 25 pushes the outer end of the lever 23 to the right as the parts are viewed in Fig. 6, thus moving the lever 23 in a counter-clockwise direction and causing the fulcrum 24 to move to the right, that is, inwardly relative to the body 10. In other words, in the opening of the door the hinge axis 17 is moved from a point behind the plane of the outside of the body (Fig. 3) to a point a predetermined distance outside the

body (Fig. 6), and in the closing of the door, the hinge axis is returned. By virtue of this hinge construction, I secure a flush exterior at the joint line. The absence of the unsightly projecting hinges greatly improves the appearance of the car and, of course, such a feature is particularly appropriate for cars of streamlined design.

The hinge 12', illustrated in Figs. 9 to 12, differs from that just described mainly in the matter of the mechanism for sliding the body member 15' back and forth in the swinging movement of the door member 16' relative thereto in the closing and opening of the door. In this form of the invention, a gear sector 41 is mounted on the door member 16' and has internal teeth 15 meshing with a spur gear 42 of a gear cluster 42-43 mounted on a spindle 44 on the body member 15'. The latter is slidable in ways 22' provided in a guide 19' for movement to and from the extended position shown in Fig. 12. The guide 19' has a rack 45 provided thereon extending lengthwise with respect to the guides 22', and the gear 43 of the aforesaid cluster is arranged to run along this rack when the cluster is turned by means of the sector 41 in the opening or closing of the door. In the opening of the door, it is obvious that the cluster will be turned in a clockwise direction, as the parts are viewed in Figs. 9 and 12, so that the body member 15' of the hinge 12' will accordingly be moved outwardly with respect to the body in the travel of the gear 43 along the rack 45. The reverse is true in the closing of the door. The opening of the door is limited, as shown in Fig. 12, by the engagement of the door panel with the back of the body member 15', although, of course, any other method of limiting the movement might be used.

The hinges shown in Figs. 13 to 16 closely resemble that of Figs. 9 to 12. The principal difference lies in the substitution of a supporting link 46 for the body member 15'' of each of the hinges 12'' and 13'' in place of the guide 19''. The link 46 is pivoted at its lower end to the inwardly and outwardly movable body member 15'', as indicated at 47, and is supported at its upper end on the door pillar of the body on a suitable pivot stud 48. A guide 49 on the door pillar holds the link 46 in a certain plane for oscillation to and fro in the opening and closing of the door, and may also be relied upon for limiting the movement of the door in opening, as by simply providing a stop thereon for engagement with the link 46. In this form, as in the one of Figs. 9 to 12, a sector 41' carried on the door member 16'' turns the gear 42' so as to rotate the companion gear 43' of the cluster and cause it to travel along the rack 45' fastened to the door pillar. The gear 43' in this construction is provided with teeth of sufficient width to maintain meshing engagement with the rack 45' in any position of the link 46, it being apparent that as the links swing outwardly, the door will be raised slightly and as the links swing inwardly the door is lowered to its normal elevation.

It is believed the foregoing description conveys a good understanding of the objects and advantages of my invention. The showing of several different constructions should serve to indicate in a measure to what extent the structure of the present invention may be modified without departing from the spirit and scope of the invention. The appended claims have accordingly been drawn with a view to covering all legitimate modifications and adaptations.

I claim:

In a hinge and mounting therefor, the combination of relatively pivoted hinge members, a guide whereon one of said members is reciprocable, an actuating lever for reciprocating said last-mentioned member mounted thereon for oscillation, means providing a movable pivotal connection between the inner end of said lever and the

10 said guide, and means providing a link connection between the outer end of said lever and the

other hinge member, said guide having a slot provided therein for the projection therethrough of the inner end of said lever, said lever having oscillatory movement in said slot in the reciprocatory movement of the hinge member, and one end of said slot serving by abutment therewith of the lever to limit movement of the hinge member in one direction.

5
